UNITED STATES PATENT OFFICE

164,071

CHILD'S CRIB OR SIMILAR ARTICLE

Edward J. Stefan, Tucson, Ariz.

Application January 27, 1950, Serial No. 7,529

Term of patent 14 years

(Cl. D5—5)

To all whom it may concern:

Be it known that I, Edward J. Stefan, a citizen of the United States, residing at Tucson, in the county of Pima and State of Arizona, have invented a new, original, and ornamental Design for a Child's Crib or Similar Article, of which the following is a specification, reference being had to the accompanying drawing, forming a part thereof, and in which:

Figure 1 is a perspective view of a child's crib or similar article showing my new design.

Figure 3 is a transverse sectional view of a child's crib or similar article showing my new design.

I claim:

The ornamental design for a child's crib or similar article, as shown.

EDWARD J. STEFAN.
